DESIGN FOR A BROOCH OR SIMILAR ARTICLE

Myrtle Baer, New York, N. Y.

Application January 30, 1943, Serial No. 109,383

Term of patent 3½ years

To all whom it may concern:

Be it known that I, Myrtle Baer, a citizen of the United States of America, residing in New York city, county of New York, and State of New York, have invented a new, original, and ornamental Design for a Brooch or Similar Article, of which the following is a specification, reference being had to the accompanying drawing, forming part thereof.

Fig. 1 is a plan view of a brooch or similar article showing my new design.

Fig. 2 is an edge view thereof.

I claim:

The ornamental design for a brooch or similar article, substantially as shown.

MYRTLE BAER.
